UNITED STATES PATENT OFFICE.

ORLA H. WATKINS, OF CLINTON, IOWA, ASSIGNOR TO GLOBE MANUFACTURING COMPANY, OF PERRY, IOWA.

WASHING-MACHINE.

1,281,725.

Specification of Letters Patent.

Patented Oct. 15, 1918.

Original application filed January 26, 1909, Serial No. 474,270. Divided and this application filed February 23, 1915. Serial No. 10,021.

To all whom it may concern:

Be it known that I, ORLA H. WATKINS, a citizen of the United States, and a resident of Clinton, in the county of Clinton 5 and State of Iowa, have invented certain new and useful Improvements in Washing-Machines, (division of my application Serial No. 474,270, filed January 26, 1909,) of which the following is a specification.

10 The invention relates to washing machines, and, more particularly, to machines designed principally for hand operation and having a reversely reciprocating rubber. It will be obvious, however, that certain features of the invention are of use in other combinations and relations.

20 The object of the present invention is to provide a washer equipped with a simple, inexpensive and efficient power momentum device, and also equipped with novel means for transmitting energy to said momentum device, and for applying the stored energy to the reversely reciprocating rubber of the machine.

25 With these and other objects in view, the invention consists in the construction and novel combination of parts hereinafter fully described, illustrated in the accompanying drawings and pointed out in the claims here- 30 to appended.

In the drawings, Figure 1 is a vertical sectional view of a washer constructed in accordance with this invention.

Fig. 2 is a horizontal sectional view taken 35 substantially on the line 2—2 of Fig. 1.

Fig. 3 is a detail plan view illustrating the arrangement of the gearing for reversely rotating the upper shaft.

Fig. 4 is a vertical sectional view illustrating a modification of the invention.

Fig. 5 is a horizontal sectional view on the line 5—5 of Fig. 4.

Fig. 6 is a detail elevation illustrating the construction of the operating lever and the 45 upright links of the washing machine.

Fig. 7 is a detail sectional view illustrating the construction of the slide.

Like numerals of reference designate corresponding parts in all figures of the drawings.

The power momentum device, illustrated in Figs. 1 to 3 inclusive of the drawings, comprises in its construction a rotary frame

1 and a pair of centrifugally operable weights 2, movable inwardly and outwardly 55 with the speed of the rotary frame and guided in their movements by inclined rods, 3, which cause the weights to rise as they move outward and to lower as they move inward. The rotary momentum device is 60 automatic in its operation, the weights being thrown upward and outward by centrifugal force and being moved downward and inward by gravity.

The rotary frame 1 includes the guide 65 rods 3, a top connecting bar 4 and means for journaling it, the journaling means, in the embodiment of the invention shown in Fig. 1, consisting of a continuous vertical shaft 5, having its upper end 6 journaled in a suitable bearing, of a horizontal bar or brace 7 and stepped at its lower end 8 in a suitable bearing 9, supported by cross bars 10, but the intermediate portion of the vertical shaft may obviously be omitted without affecting 75 its operation, the upper and lower journals only being essential. The horizontal top connecting bar is centrally secured to the upper end of the shaft 5, and its terminal portions 11 are bent downward and outward, 80 being arranged at an inclination and pierced by the upper ends of the guide rods 3. The lower ends of the guide rods are suitably secured to the lower portion of the shaft 5.

The weights 2 are preferably in the form 85 of balls, and their inward and outward movements are cushioned by inner and outer cushioning devices, consisting of coiled springs 12 and 13, disposed on guide rods at the inner and outer ends or portions of the 90 slidable weights 2, which are provided with openings 14 through which the guide rods pass. The terminal portions 11 of the top connecting bar 4 are substantially perpendicular to the guides and are arranged to 95 form abutments for the upper cushioning springs 13. The rotary momentum device is not of sufficient weight to appreciably affect the starting of the machine, but as the speed of the machine increases the weights 100 are thrown outward and form an efficient momentum device, rendering the operation of the machine steady and uniform.

The momentum device will be found advantageous in manually operated machines, 105 and especially in those equipped with up-

right operating levers, such as that illustrated in Fig. 1. The operating lever 15 is fulcrumed at an intermediate point at one side of the tub or receptacle 16, and is connected at its lower end by a rod 17 with horizontally disposed speed increasing gearing, consisting of a relatively large gear 18 and a pinion 19, which is mounted on the shaft 5 at the lower end thereof. The upper portion of the lever is connected by links 20 with a slidable rack bar 21, which meshes with a gear 22 of an upper or agitator shaft 23.

Figs. 4 to 6 illustrate a modification. The weights 24, which are in the form of balls, are carried by the lower ends of the arms or levers 25, located at opposite sides of a lower rotary shaft 26, and connected at their upper ends with the same by a slide 27, and also connected at intermediate points with the said shaft by links 28. The shaft 26 is preferably square in cross section, and the slide 27 is in the form of spaced plates, located at opposite sides of the shaft and pivoted at their ends to the upper terminals of the weighted arms or levers 25. The links 28 diverge upwardly and are connected at their lower ends to the shaft by a suitable pivot 29. The upper ends of the links are connected with the arms or levers 25 by pivots 30 and form fulcrums for the weight-carrying arms or levers. When the shaft 26 is rotated, the weights 24 move inward and outward as the speed of the shaft increases and diminishes. The weights are thrown upward and outward by centrifugal force and are moved downward and inward by gravity.

The vertical shaft 26, which is journaled in suitable bearings, carries a pinion 31, meshing with a relatively large gear 32, which is connected by a rod 33 with an operating lever 34. A spring 35 is connected with the rod 33 to prevent a dead center.

The lever is connected at the upper portion by inner and outer links 36 and 37 with a rack bar 38, which reversely rotates an agitator shaft 39 through a pinion similar to that heretofore described. The upright links 40 and 41 are employed for maintaining the inner and outer links 36 and 37 in operative position.

What I claim is:

1. In apparatus of the class described, a balance governor comprising a vertical shaft mounted for rotation, arms fixed to and extending horizontally in opposite directions from said shaft and having their outer ends turned downwardly, rods mounted in inclined positions beneath said arms, said rods fixed at one end each to said shaft, said rods extending outwardly from said shaft and fixed at their outer ends to the down-turned

ends of said arms, and weights slidably mounted on the inclined rods. 65

2. In apparatus of the class described, having a vertical shaft, an automatic balance governor, comprising arms radiating from said shaft and having their outer ends turned downwardly, inclined rods fixed to the shaft below the arms and fixed to the down-turned ends of said arms, cushions on the outer ends of said rods, and weights slidably mounted on said rods. 70

3. In apparatus of the class described, a support, a vertically extending shaft journaled within said support, a pair of diametrically extending arms carried by the upper end of said shaft and extending equi-distant on each side thereof, angular extensions 80 formed at the extremities of said arms, supporting rods connecting said angular extensions with the said shaft, weights slidably mounted upon said rods and arranged to be shifted outwardly by centrifugal force due to the rotation of said shaft and cushioning members carried by each end of said weights to limit the movements thereof for the purpose specified. 85

4. In apparatus of the class described, a power momentum device comprising a rotary shaft, outwardly extending rods secured to said shaft to rotate therewith, weights 90 slidable along said rods, means to normally cause said balls to move toward said shaft when at rest, means to rotate said shaft whereby said balls will move outwardly from said shaft in proportion to the speed of rotation, and means for rigidly bracing the outer end of each of said rods against lateral movement. 95

5. In apparatus of the class described, a power momentum device comprising a rotary frame journaled at the top and bottom and including upwardly diverging inclined 105 guides, and a top connecting bar secured at its terminals to the upper ends of the guides, and weights slidable along the guides.

6. In apparatus of the class described, a power momentum device comprising a rotary frame including upwardly diverging inclined guides, upper and lower journals arranged at the top and bottom of the frame, and a top bar connecting the guides and having inclined terminal portions, 110 weights, slidable along the guides, and cushioning means supported by the guides and located above and below the weights. 115

In witness whereof, I hereunto subscribe my name this 2nd day of January, A. D. 120 1915.

ORLA H. WATKINS.
